UNITED STATES PATENT OFFICE.

FRANK MILLER, OF BATESVILLE, OHIO, ASSIGNOR OF ONE-HALF TO W. J. SHIVELY AND JAMES R. KEENAN, BOTH OF SAME PLACE.

CAR-COUPLING.

SPECIFICATION forming part of Letters Patent No. 449,633, dated March 31, 1891.

Application filed December 5, 1890. Serial No. 373,684. (No model.)

To all whom it may concern:

Be it known that I, FRANK MILLER, a citizen of the United States, residing at Batesville, in the county of Noble and State of Ohio, have invented a new and useful Car-Coupling, of which the following is a specification.

This invention relates to car-couplings; and the object of the same is to effect improvements upon couplings of this same general character heretofore constructed.

To this end the invention consists in the details of construction hereinafter more fully described and claimed, and as illustrated in the drawings, in which—

Figure 1 is an elevation of the end of a box-car, showing my improvements as applied thereto. Fig. 2 is a central longitudinal section of the draw-head in its normal position without the link. Fig. 3 is a similar section with the pin raised to release the link and the link supported by the link-lifter. Fig. 4 is a similar section showing the link locked in position and under tension.

Referring to the said drawings, the letter C designates the body of the car, below which is arranged a draw-head D, which is of the ordinary construction, except as hereinafter specified. Mounted in eyes H in the ends of the car-body is a horizontal rod h, having depending ends h' and an upwardly-extending handle h''. Depending from this rod is a lever K, which is connected with the pin J in a manner hereinafter described, and connected to the end of the car is a spring M, preferably of the construction shown, which bears upon the lever K and forces it normally inward.

g is a cleat secured to the end of the car, and pivotally mounted on a pin G therein is a lever i, one of whose ends is connected by a chain S with an eye P in the top of the draw-head. By this means an operator standing by the side of the car can manipulate the lever i to raise and lower the draw-head for the purpose of guiding the link into the mouth of an approaching draw-head.

Pivotally mounted on a horizontal bolt S' through the draw-head is the link-lifter D', which is of the shape shown in the drawings.

50 In eyes c in the bottom of the draw-head is

mounted a bar E, around which are passed the coils of a spring F, whose free end presses downwardly on the rear end of the link-lifter and throws its front end upwardly. Said front end is provided with a notch N, whose 55 rear approach n is beveled, as shown, and the notch passes over a square bar Q, which is seated through the draw-head. The spring F causes the front end of the link-lifter to be normally raised, as above stated, and the link 60 T is therefore normally held in direct alignment with the draw-head, as shown in Fig. 3, except under conditions hereinafter stated.

The letter J designates the pin, which is of L shape, pivoted at its angle on a bolt Q', 65 passing transversely through the draw-head, and the upper end of this pin is connected by a link L' with the lower end of the depending lever K. By reason of the fact that the spring M bears this depending lever K to the 70 rear the upper end of the link J is also borne in that direction and the lower end thereof normally thrown downward through the link. As the latter is driven into the draw-head, the pin is turned to the rear on its pivot Q' and 75 the link-lifter D' is slightly depressed. A tension being imparted to the link, the pin is drawn forward until its lower end rides up the beveled approach n and depresses the link-lifter D', as shown in Fig. 4, the lower 80 end of the pin then striking the square bar Q and firmly holding the link. A continued tension upon the link will hold the parts in this position with the front end of the link-lifter depressed and out of contact with the 85 link, whereby the latter will be allowed a limited amount of play in all directions, according as the exigencies of the case may demand. As soon as the tension on the link ceases the link-lifter will rise and the link 90 will be rigidly held, as shown in Fig. 3. The pin may be then raised by operating one of the ends h' or the handle h'' from either side or from the top of the car. The advantages of this construction other than those set forth 95 above will be obvious after a short use of the device.

I do not intend to be limited to the exact details of the construction illustrated in the drawings, it being obvious that changes may 100

be made therein within the skill of a mechanic without departing from the spirit or scope of the invention.

What is claimed as new is—

- 5 1. In a car-coupling, the combination, with a draw-head loosely supported beneath the car, a lever pivoted to the end of the car, and a chain connecting said lever with the draw-head, of a pin pivoted in said draw-head, a shaft journaled across the end of the car and carrying operating-handles, a lever connected to and depending from said shaft, and a link connecting said lever with the pin, substantially as described.
- 15 2. In a car-coupling, the combination, with a draw-head, a spring-actuated link-lifter pivoted in the bottom of said draw-head and having a deep notch in its upper face, whose rear approach is beveled, and a bar through the draw-head normally resting in said notch, of a pin pivoted in the upper side of the draw-head with its lower end normally in contact with said approach, and means for operating said pin, substantially as described.
- 25 3. In a car-coupling, the combination, with

a draw-head loosely supported beneath the car, a lever pivoted to the end of the car, a chain connecting said lever with the draw-head, a spring-actuated link-lifter pivoted in the bottom of the draw-head and having a deep notch near its front end in its upper face, the rear approach to said notch being beveled, and a bar through the draw-head resting in said notch, of a pin pivoted in the upper side of the draw-head with its lower end normally in contact with said approach, a pin-operating lever, a spring pressing the same to the rear, a link connecting the lower end of said lever with the coupling-pin, and handles for operating said lever, all substantially as and for the purpose hereinbefore set forth.

In testimony that I claim the foregoing as my own I have hereto affixed my signature in presence of two witnesses.

FRANK MILLER.
